PACKAGING TRAY

Carlo Caprioli, Montreal, Quebec, Canada, assignor to
Plastic Packaging Products Limited, Montreal, Quebec,
Canada

Filed Sept. 4, 1962, Ser. No. 71,527

Term of patent 14 years

(Cl. D58—13)

FIGURE 1 is a perspective view of a packaging tray, showing my new design; and

FIGURE 2 is a vertical sectional view taken substantially on the plane of line 2—2 of FIGURE 1.

The tray is formed of substantially paper-thin molded plastic in which the undersurface is a reverse image of that shown in FIGURE 1.

The characteristic feature of my design resides in the combination of vertically corrugated double-walled peripheral walls integral with a raised bottom in which the low side walls merge into higher end walls at the corners and the relatively smooth surfaced double-walled parti-

tion panel having an upper corrugated edge at the height of the raised end walls as shown.

I claim:

The ornamental design for a packaging tray, as shown and described.
